UNITED STATES PATENT OFFICE.

WARREN S. BARTLE AND JOHN E. STUART, OF NEWARK, NEW YORK.

WINDOW-SCREEN.

SPECIFICATION forming part of Letters Patent No. 242,180, dated May 31, 1881.

Application filed March 30, 1881. (No model.)

To all whom it may concern:

Be it known that we, WARREN S. BARTLE and JOHN E. STUART, both of Newark, county of Wayne, State of New York, have invented 5 certain new and useful Improvements in Window-Screens, of which the following is a full, clear, and exact description, reference being had to the accompanying drawings, making part of this specification, in which—

10 Figure 1 is a perspective view of a window-frame with our improved screen applied. Fig. 2 is a vertical transverse section through the same. Fig. 3 represents a vertical section through a part of the window-frame showing from the inner side the relation of the screen-frame thereto. Fig. 4 is a perspective view of the screen removed from the window.

Our invention relates to a novel construction 20 of the screen-frame, whereby it is adapted to be readily applied within the groove for the sash when the latter is raised, and to snugly close the opening without the aid of adjustable or removable parts; and it consists in making the frame of a width corresponding to the 25 width of the lower sash, or of the openings therefor in the window-frame, less the amount of projection of one of the stops or strips forming the groove for the sash, so that when one side of the screen-frame is inserted in the groove 30 for the sash on one side the other side will pass by the projecting stop or strip on the opposite side of the window-frame, and in providing said screen-frame with a strip flange or flanges for spacing it or causing it to overlap evenly 35 the outer stops or guide-strips and for holding it out snugly against the same, as hereinafter described.

In the accompanying drawings, A represents the window-frame; A', the sill thereof inclining outward; B, the lower sash, and a a' the stops or strips forming the grooves or ways in which said sash moves, said parts being constructed and arranged in the usual or any preferred manner.

45 C represents the screen complete, removed from the window in the perspective view, Fig. 4.

The frame is composed of the vertical side strips, c' c², and the top and bottom strips or bars, c³ c⁴, neatly framed or secured together 50 and giving a width of frame equal to the width of the sash B, whose place it is designed to

occupy, less the amount of projection of the guide-strip a or a' on one side of the frame A, thereby adapting it when one side of the screen-frame is placed in the sash channel or groove 55 on one side to allow the opposite side to pass or move by the stop or strip on the opposite side of the window-frame. The side and top bars, c' c² c³, of the screen-frame are of reduced thickness as compared with the sash-frame, 60 while the lower bar, c⁴, is, by preference, made of sufficient thickness to about snugly fill the sash-groove, thus making it project beyond the inner face of the side bars, c' c², as shown. The upper horizontal frame-bar, c³, has a rabbet 65 formed in its upper face, or a strip may be rigidly secured to its outer face and made to project above the bar c³, as shown at d. This strip or flange is made shorter than the bar c³, and of a length adapting it to fit snugly between 70 the outer strips, a a, between which it rests when the screen-frame is in place. The frame projects equally on each side beyond the ends of the strip d, and the latter being formed upon or secured to the outer face of the frame-bar 75 c³, as shown, when the strip d is forced outward between the outer stops, a, the sides of the screen-frame will rest against and overlap evenly the inner faces of said strips or stops a, as shown in Fig. 3, when the sash being let 80 down inside of the strip d, as shown in Fig. 2, the top of the screen-frame will be held snugly out against said stops or strips. The bottom of the frame will be held out by the bottom-bar, c⁴, to which increased thickness may be 85 given, as explained, or it may be held by the aid of the outwardly-inclined face of the sill A', which, with the added weight of the sash when the screen-frame is in place, will serve to hold it pressed out at the bottom without the 90 aid of the increased thickness of the lowerframe-bar referred to.

Short blocks may be used at the ends of the upper bar, c³, instead of the continuous strip d, and similar blocks may be applied at the 95 ends of the lower bar, instead of making it thicker throughout its entire length, with the same result.

By the construction described the screen is made to snugly fill the opening made by raising the sash, and this without the aid of adjustable parts or pieces, thereby greatly sim-

plifying the construction and reducing the cost thereof, while at the same time fully accomplishing all that the screen-frame is designed to accomplish.

5. The screen itself may be made of any usual or preferred material, applied to the frame in any convenient or preferred manner.

Having now described our improvements, we claim—

10. 1. A window-screen frame adapted, without the aid of adjustable part or parts, to pass within the sash groove or channel, in combination with the projecting spacing strip or flange for causing it to overlap evenly the guiding strips

or stops on the opposite sides of the window-frame, and for holding it snugly against said strips, substantially as described.

2. The screen-frame provided with the projecting strip or flange *d*, and with the sill or lower frame-bar, *c*, of greater thickness than the side and top bars, substantially as and for the purpose described.

WARREN S. BARTLE.

JOHN E. STUART.
